COMBINATION GARMENT HANGER AND STRETCHER

Vincent Bivona, Westfield, N. J.

Application March 7, 1934, Serial No. 714,505
Renewed September 28, 1935

3 Claims. (Cl. 223—62)

This invention relates to the broad class of apparel and garment hangers and has more particular reference to a composite or versatile device such as is now referred to in the trade as a combination hanger and stretcher, the same being especially but not necessarily, adapted for stretching and drying union woolen underwear and garments.

Needless to say, I am aware of the fact that devices of this general type are not new and that the prior art to which the invention relates exemplifies similar structural assemblies. Therefore it is my primary aim to generally improve upon prior art devices by providing one characterized by certain structural improvements and refinements calculated to render the device distinctive and capable of fulfilling the requirements in a more dependable and satisfactory manner.

Other features and advantages will become more readily apparent from the following description and drawings.

In the drawings:

Figure 1 is an elevational view of a device constructed in accordance with the principles of the present invention.

Figure 2 is an edge elevational view thereof, that is observing Figure 1 in a direction from right to left.

Figure 3 is a view in section and elevation disclosing the structural arrangement and selection of features a little more in detail.

Figure 4 is an enlarged fragmentary sectional end elevational view at right angles to Figure 3 showing the upper portion only.

Figures 5 and 6 are cross sections taken on the horizontal lines 5—5 and 6—6 respectively of Figure 4.

Referring now to the drawings by distinguishing reference characters it will be observed that the numeral 6 designates a vertically elongated tubular box of wood or equivalent material which is unitarily described as a casing. This embodies four panels or boards which may be described as a pair of duplicate end boards 7 between which are nailed or otherwise fastened a pair of companion spaced parallel facing boards or panels 8. It will be noticed in Figure 1 that the upper end portions 9 of the boards 8 extend above the upper beveled edges of the end boards 7 and are secured to the central or crotch portion of the substantially V-shaped main hanger or head 10.

The casing is adapted to accommodate a number of details. First I call attention to a slide 11 which as shown in Figure 3 is bifurcated, the

furcations being designated by the numeral 12 and extending slidably into the tubular casing. Attached to the free or upper ends of these furcations is a feed nut 13 to accommodate the threaded portion 14 of the feed screw 15. The upper smooth portion of this screw extends through a centralized guide in the upper hanger or head 10. The upper end of the shaft or feed screw is formed with a hand crank 16 by which it may be conveniently rotated to adjust the slide 11 in or out of the casing.

At this time attention is called to a substantially U-shaped bracket or adapter 17 which is fastened in the upper end portion of the casing between the end boards 7, the central part of this being apertured to serve as a support and guide for the shaft or screw 15. Incidentally pins or the like 18 are carried by the shaft and located above and below the plate to provide the desired assembling and retaining connection. Thus it will be seen that the feed shaft is swivelly hung in the casing and threadedly connected to the extensible and retractable slide 11. On its lower end the slide is provided with a supplemental or somewhat smaller V-shaped head or hanger 19 which cooperates with the first named head 10. With this arrangement the heads 10 and 19 may be moved toward and from each other for stretching the garment in an obvious manner as the feed screw or shaft is turned.

I desire to mention further that the upper end portion of the shaft 15 is provided with a suspension hook or equivalent element 20 by means of which the device, as a whole, is conveniently suspended from a rod or supporting hook in the clothes closet or elsewhere.

It is obvious, of course, that the heads 10 and 19, which are of conventional V-shaped form can be used as independent hangers for coats and garments. These heads however can be used collectively for stretching the legs of men's trousers by adjusting the heads toward and from each other as conditions require. The leg portions of the trousers can be suitably attached to the heads to permit the stretching operation to be satisfactorily accomplished.

Briefly the device comprises a substantially rectangular longitudinally elongated box like casing fastened at its upper end to the central portion of a V-shaped or conventional type of coat hanger, a slide mounted for extension and retraction in said casing, operating means attached to the slide and cooperable with the casing and coat hanger, and means on the lower

end of the slide for operable connection with the adjacent part of the garment to be stretched.

It is thought that persons skilled in the art to which the invention relates will be able to obtain 5 a clear understanding of the invention after considering the description in connection with the drawings. Therefore, a more lengthy description is regarded as unnecessary.

Minor changes in shape, size, and rearrangement 10 of details coming within the field of invention claimed may be resorted to in actual practice, if desired.

Having thus described my invention, what I claim as new is:

- 15 1. A structure of the class described comprising a main garment hanger, a casing attached to the central portion thereof, said casing being of longitudinally elongated type, an adapter bracket mounted in said casing, a feed shaft rotatably connected with the central portion of said head and with said adapter bracket, said shaft having a screw threaded portion and having its upper end formed into a hand crank and equipped with a suspension hook, a slide mounted for extensible 25 and retractable movement in said casing and including a feed nut with which the threaded portion of said shaft is operatively connected, and a stretching head secured to the lower end of said slide.
- 30 2. In a structure of the class described, a substantially V-shaped garment hanger, an elong-

gated box like casing embodying end boards and facing boards, the facing boards being attached at their upper ends to the intermediate portions of said hanger, a feed shaft mounted for rotation in said casing and rotatably connected with the central portion of said hanger, the upper end of said shaft being provided with an operating crank, a slide mounted for movement in said casing, said slide being bifurcated, the furcations being provided with a feed nut, said shaft having 10 a screw threaded portion operatively connected with said feed nut and located between said furcations, and garment attaching means secured to the lower end of said slide.

3. In a convertible garment hanger and 15 stretcher structure, a relatively large substantially V-shaped member, a comparatively small V-shaped member associated with said first named member and disposed in longitudinally spaced parallelism, both of said members being 20 fashioned to function as selectively usable garment hangers as well as garment stretching and shaping devices, longitudinally extensible and contractible adjusting means disposed between and connected with said members, and manually regulated means associated with said adjusting means for actuating the latter, said regulating means being located above the central portion of said first named member to render it accessible and including a suspension hook.

VINCENT BIVONA. 30
